UNITED STATES PATENT OFFICE.

WALTER S. FRAZIER, OF AURORA, ILLINOIS.

SULKY.

SPECIFICATION forming part of Letters Patent No. 253,276, dated February 7, 1882.

Application filed July 2, 1881. (No model.)

To all whom it may concern:

Be it known that I, WALTER S. FRAZIER, residing at Aurora, in the county of Kane and State of Illinois, and a citizen of the United States, have invented a new and useful Improvement in Sulkies, of which the following is a full description, reference being had to the accompanying drawings, in which—

Figure 1 is a top or plan view; Fig. 2, a side elevation with the wheel B' removed.

The object of this invention is to give the foot-rest bars a yielding or spring support at their rear ends upon the axle independently of the seat-supports; and its nature consists in providing a spring-support between the foot-rest bars and the axle, which spring or yielding support shall be independent of the seat-supports.

In the drawings, A indicates the axle; B B', the wheels; C, the shafts; D, the connecting-bar of the shafts; E, the foot-rest; F, the foot-rest supporting-bars; a, springs; b, pins or bolts for keeping the foot-rest bars or springs in position.

The axle A, wheels B B', and shafts C may be made in any of the usual and well-known forms. As shown, the bars F are pivoted to the cross-bar D; but they may be connected directly to the shafts by clips or other suitable means, and they are curved or carried down-

ward, so as to bring the foot-rest in a proper position, and, as shown, their rear ends are turned upward, so as to bring them a sufficient height above the axle for the proper insertion of springs; but they may run to or under the axle and be supported or suspended by springs.

The springs a, as shown, are coiled springs; but it is evident that many of the known varieties of springs may be used to take their places. The central pin, b, passes up through the spring and through the bars F, as shown, to keep the bars and springs in position. In some of the forms of springs which may be used such central pin would not be required.

A seat of the form shown or of other suitable form is to be used in connection with this foot-rest; but the form or manner of supporting the seat from the shafts or cross-bar D, or partly from both, is not material, and the seat may also be wholly or partly supported by separate springs connected with the axle.

What I claim as new, and desire to secure by Letters Patent, is—

The bars F, in combination with the springs a and axle A, substantially as specified.

WALTER S. FRAZIER.
